UNITED STATES PATENT OFFICE.

CHARLES HAGGERTY, OF PAWTUCKET, RHODE ISLAND, ASSIGNOR TO NEW ENGLAND BUTT COMPANY, OF PROVIDENCE, RHODE ISLAND, A CORPORATION OF RHODE ISLAND.

CARRIER FOR BRAIDING MACHINES.

Application filed February 9, 1928. Serial No. 252,960.

- This invention relates to an improved construction of carrier for braiding machines; and has for its object to provide in such a carrier a guide standard for a tension weight 5 which is slidably mounted thereon and a tension spring arranged to act between the standard and the weight to accelerate the take-up action on the yarn when running at a high speed.
- 10 A further object of the invention is to mount a guide rod on the weight member and mount a coil spring on the rod to act upon and cause a quick return motion of the weight after having been lifted.
- 15 The invention further consists in the provision of a control latch for the package having a latch for the package having a latch lift member guided to slide through a boss in the weight standard; also to mount the weight on 20 this standard and a spring to act between the standard and the weight to accelerate its take-up action on the yarn.

With these and other objects in view, the invention consists of certain novel features 25 of construction, as will be more fully described, and particularly pointed out in the appended claims.

In the accompanying drawings:

Figure 1 is a side elevation showing my 30 improved construction of carrier with the tension weight in partly lifted position.

Figure 2 is a perspective view showing the weight standard and the latch lift member as guided in bosses on the standard, also 35 showing the weight in partly lifted position.

Figure 3 is the same as Figure 2 with the exception that the weight is raised to the top of the travel and engaging the latch lift to operate the latch and release more yarn.

40 Figure 4 is a perspective view of the take-up weight showing the spring carrying guide rod mounted thereon.

Figure 5 is a perspective view of the upper portion of the weight standard showing two 45 guide bosses mounted thereon.

Figure 6 is a sectional elevation of the weight standard through the guide bosses.

Figure 7 is a rear view of the weight standard with the weight mounted thereon and 50 showing the guide rod to one side of the center of the standard and extending through the standard bearing.

It is found in the practical construction and operation of braiding carriers of this

character, of advantage to construct a weight 55 standard with a boss through which the turned down end of the latch lift rod is guided and to also provide a boss on this standard through which the spring carrying rod which is attached to the weight may be 60 guided, this rod boss also serving as an abutment between which and the weight the spring may act to accelerate the take-up action of the weight upon the yarn causing the carrier to function properly while running at a high rate of speed; and the following is a detailed description of the present embodiment of my invention and showing 65 one arrangement of parts by which these advantageous results may be accomplished:

With reference to the drawings, 10 designates the body of a carrier which is provided with a package spindle 11 on which the package 12 may be mounted; also a weight standard 13 is mounted upon this body member, which is preferably cast integral with the body and is of an oval shape in cross section to receive and guide the yarn tension weight 14 to slide vertically thereon. This standard is herein shown as being provided with a 70 front boss or lug 15 which is drilled at 16 to guide the downwardly turned end 17 of the latch lift 18, the opposite end of the latch lift being connected as at 19 to the latch 20, which is mounted to rock on the fulcrum pins 21, 75 the latch being provided with a tooth 22 to engage teeth 23 in the bottom of the package spool 24.

This weight standard 13 is provided on its rear with another boss 25 which is drilled at 90 26 to serve as a sliding bearing for the spring guide rod 27, the lower end of which rod is threaded as at 28 and screwed into the tapped hole of the weight 14. On this weight rod, I have mounted a coil spring 29 its upper end abutting against the under side of the boss 25, while its lower end abuts against the weight 14, thereby acting upon this yarn tension weight to accelerate its yarn take-up action, causing the weight to function and 95 quickly take up the slack of the yarn while the carrier is running at a high velocity.

By my improved arrangement of tension spring in the carrier the yarn take-up action on the tension weight is greatly accelerated 100 permitting the carrier to be run at a much greater velocity than would be possible without the assistance of such a spring.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A carrier for braiding machines having a package spindle, a weight guide standard, a tension weight slideable on the standard, a rod carried by the weight, a spring coiled about the rod to act upon the weight, and a feed control latch operated by the movement of said weight.
2. A carrier for braiding machines having a package spindle, a tension weight guide standard, a weight slideable on the standard, an abutment on the standard, a tension spring located to one side of the standard and acting between said abutment and said weight, and a feed control latch operated by said weight.
3. A carrier for braiding machines having a package spindle, a weight guide standard, a tension weight slideable on the standard, a guide rod carried by the weight, a guide boss on the standard for said rod, a spring on the rod acting between said boss and weight and a feed control latch operated by movement of said weight.
4. A carrier for braiding machines having a package spindle, a weight guide standard,

a package control latch, a latch lift guided in said standard, a weight on the standard, a rod carried by the weight and also guided in the standard, and a spring on the rod arranged to act on the weight and said weight being arranged to engage the latch lift to operate the latch.

5. A carrier for braiding machines having a package spindle, a weight guide standard having a guide boss thereon above the weight travel, a package feed control latch, a latch lift connected at one end to the latch with its opposite weight engaging end turned down to extend through and receive a bearing in said boss, a latch operating weight on the standard and a spring acting upon the weight to accelerate its take-up action upon the released yarn after operating the latch.

6. A carrier for braiding machines having a package spindle, a weight guide standard, a package feed control latch, a latch lift member connected to the lift and having a down turned end slidably supported in a bearing in said standard, a latch operating weight on the standard, a rod carried by the weight also slidably supported in the standard, and a spring on the rod acting upon the weight to accelerate its take-up action after having engaged the lift to release more yarn.

In testimony whereof I affix my signature.

CHARLES HAGGERTY.
